UNITED STATES PATENT OFFICE.

FRANK FICHT, OF ISLE ROYAL MINE, MICHIGAN.

IMPROVEMENT IN DUMPING APPARATUS.

Specification forming part of Letters Patent No. 44,412, dated September 27, 1864.

To all whom it may concern:

Be it known that I, FRANK FICHT, of Isle Royal Mine, in the county of Houghton and State of Michigan, have invented a new and Improved Dumping Apparatus; and I do hereby declare that the following is a full, clear, and exact description thereof, which will enable those skilled in the art to make and use the same, reference being had to the accompanying drawings, forming part of this specification, in which—

Figure 1 is a side sectional elevation of my invention. Fig. 2 is a plan view of the same.

Similar letters of reference indicate corresponding parts.

This invention pertains to the class of devices that are employed for elevating ores, minerals, earthy matters, and other substances from mines, wells, excavations, and subterranean places of all kinds.

A represents the upper termination of the usual railroad-track or "skip-road" rising from the mouth of a mine. A' A² are extension-rails attached to A, as shown. B is the skip or dumping car in which the ore or other substance to be moved is carried. The car B is provided with flanged wheels to keep it upon the track in the usual manner. The car B is propelled or drawn by means of a swinging bail, C, which is pivoted by ears c c to the sides of the car, as shown. Above the mouth of the mine there is a frame-work, D, across the upper part of which is journaled a suitable rope-wheel, E, over which runs the lifting-rope F, by means of which the car B is elevated, said rope being attached to the bail C, as shown. The wheel E may be so arranged over the mouth of the mine that when stretched it will not touch the track, thus leaving the latter always free and unobstructed for the introduction of timbers into the mine. At a certain distance above the mouth of the mine, where it is desirable to cause the car to dump its load, I cut horizontal recesses b b on the inside of the track-rails A A' A², so that the car B, when its front wheels arrive at the recesses b b, will pass along horizontally on the inner edges of said recesses, but the bail C will con-

tinue to move upward on the same path as before, and while the front of the car passes horizontally along the recesses b the bail will swing over the rear of the car and lift up the rear part thereof, thus inverting, or nearly inverting, the car, (as shown in red, Fig. 1,) and cause the contents thereof to be discharged. In this position of the car or skip the front wheels thereof will have passed to the extreme limit of the recesses b b into pockets b' at the end of the recesses, while the hind wheels of the car, now inverted, will ride upon and be guided by the upper rails, A', and the front wheels will run between the rails A' A². (See red lines, Fig. 1.)

Arranged upon a suitable frame, D, directly under the recesses b b, is a friction-roller or a set of friction-wheels, G, the use of which is to form a bearing surface for the front edge of the car to strike against when it is inverted, to prevent the front wheels of the car from becoming displaced or thrown off the track during the dumping operation, or during the downward starting of the car. (See red lines, Fig. 1.)

The skip or car B is to be so made and hung, and the recesses b b are to be of such a depth, that when the loaded car rises it will by its own action pass with its front wheels into the recesses b, while the body inverts itself and the hind wheels mount the track A' above the recesses b, as before described; and when the rope is lowered the rear of the car will, by its own gravity, return to its original position, and the hind wheels will run down the track A', below the recesses b b, onto the track A, and the weight of the hinder part of the car will be sufficient to draw the front wheels out of their recesses b b, and cause the descent of the skip or car into the mine for a new load.

My improvement thus constitutes a self-acting dumping apparatus, simple in construction and very effective in operation.

I do not confine myself to the particular form here shown of any of the parts, for they may be changed by the intelligent mechanic as various circumstances may require.

What I claim as new, and desire to secure by Letters Patent, is—

1. The combination of the recesses *b b* with the rails *A A' A²*, or their equivalents, substantially as herein shown and described.

2. The employment of the wheels *G*, in combination with the above-named parts,

substantially as herein shown and described.

3. The employment of the skip or car *B* in combination with the above-named parts, substantially as herein shown and described.

FRANK FICHT.
